US00D821858S

(12) **United States Design Patent** (10) Patent No.: **US D821,858 S**
(45) Date of Patent: ** Jul. 3, 2018

(54) **CLIP FOR DECKING SYSTEM**

(71) Applicant: **VALINGE INNOVATION AB**, Viken (SE)

(72) Inventors: **Marcus Bergelin**, Lerberget (SE); **Nils-Erik Engström**, Trelleborg (SE)

(73) Assignee: **VALINGE INNOVATION AB**, Viken (SE)

(**) Term: **15 Years**

(21) Appl. No.: **35/503,132**

(22) Filed: **Mar. 23, 2017**

(80) **Hague Agreement Data**

Int. Filing Date: **Mar. 23, 2017**

Int. Reg. No.: **DM/096196**

Int. Reg. Date: **Mar. 23, 2017**

Int. Reg. Pub. Date: **Jun. 9, 2017**

(30) **Foreign Application Priority Data**

Dec. 21, 2016 (EM) 003531292

(51) LOC (11) Cl. **08-08**

(52) U.S. Cl.

USPC **D8/382**

(58) **Field of Classification Search**
